CONSTRUCTION AND MANUFACTURE OF
RADIO RECEIVERSDavid Grimes, Beverly, N. J., assignor to Philco

8 Claims. (Cl. 250—16)

This invention relates to radio receivers and more particularly to certain novel structural features which greatly facilitate commercial manufacture, effect substantial reduction in the production cost, and materially improve the performance and operation of the receiver. The principal object of the invention is to provide a novel chassis structure and a novel structural arrangement of the parts or elements of a radio receiver, and to provide other specific features as set forth in detail hereinafter.

A more specific object of the invention is to provide a novel mounting for a unit including a tuning element having a control shaft, which mounting isolates the unit against extraneous vibrations, permits adjustment of the position of said shaft, and provides chimney-like structures at the sides of the unit, as fully described hereinafter.

By the present invention, it is commercially practical in the manufacture of radio receivers to employ a plurality of units, each comprising certain elements arranged in predetermined relation to one another, and to arrange the units in predetermined relation to each other. In this manner, the units may be manufactured separately and may be tested individually, so that any defects that may occur are localized in the units and it is readily possible to locate and remedy such defects, thus eliminating the necessity of examining the entire receiver to locate such defects. Moreover, it is possible by the employment of units according to the present invention to manufacture various forms of each unit and, by the use of different combinations of the said forms, to manufacture different types of radio receivers. A large number of different types of receivers may thus be manufactured or built by manufacturing a relatively small number of different units and assembling the different units in various combinations.

The employment of units according to the present invention, and the predetermined design and assembly of the units, as above mentioned, results in other important advantages. For example, as will be described in detail hereinafter, the unit including the tuning element is non-microphonically and adjustably mounted and, furthermore, by the use of the invention the sensitive parts of the receiver are isolated thermally from the heat-generating parts or elements, and the other equally important advantages are obtained.

The invention will now be described in detail with reference to the accompanying drawings as

applied to a conventional superheterodyne multi-wave band receiver, but it will be understood that the invention is not thus limited but is applicable to any type of radio apparatus.

In the drawings:

Fig. 1 is a plan view of the radio receiver with the vacuum tubes removed and before mounting in a cabinet;

Fig. 2 is a front view of the receiver;

Fig. 3 is a sectional detail view taken along line 3—3 of Fig. 1;

Fig. 4 is an exploded perspective view of a front mounting for the R. F. unit; and

Fig. 5 is a sectional detail view of the said mounting.

In accordance with the invention as disclosed in the drawings, a superheterodyne multi-band receiver may be constructed as follows:

The receiver is built in three units A, B and C. One unit A may comprise the power supply elements (transformer 1, rectifier tube socket 2, electrolytic filter condensers 3, etc.) and the audio output elements (power amplifier tube sockets 4). In receivers of this type, the field coil of the loud speaker may be used as a filter choke. A second unit B may comprise the radio frequency portion of the receiver, which includes the R. F. amplifier tube socket 5, electrolytic condenser 6, the oscillator and first detector tube socket 7, multi-wave band coils and wave-band switches (not visible), tuning condensers 10, etc. The third unit C may comprise the intermediate frequency amplifier portion of the receiver and the second detector, and may include the I. F. amplifier tube socket 11, the shielded I. F. coils 12, the second detector tube socket 13, etc. The units are assembled adjacent one another in the order named, with the second or R. F. unit B mounted between the other two units, as shown clearly in Fig. 1.

The outer unit A may comprise a base or supporting plate 14 having a depending flange 15 (see Fig. 2) at its outer edge and an upstanding flange 16 at its inner edge. Likewise, the other outer unit C may comprise a base or supporting plate 17 having a depending flange 18 at its outer edge and an upstanding flange 19 at its inner edge. The two plates 14 and 17 are mounted in predetermined space relation on two parallel bars 20 and 21 which are similar and interchangeable. The plates and their depending flanges are attached to the bars by bolts 22 or the like, and the plates thus serve to fix the bars in position and, together with the bars, serve as a chassis or foundation framework for 55

tion of Elmer O. Thompson, Serial No. 129,968, filed March 9, 1937.

To permit alignment of the condenser shaft with respect to the front of the radio cabinet, the position of the rear of the R. F. unit B is 5 adjustable as to height, the front supports 24 permitting pivotal movement of the front of the unit, as will be more clearly understood from the subsequent description of the front mountings. Thus, the entire unit B may pivot to a small ex- 10 tent about the front resilient supports 24, which permits the position of the shafts 35 and 36, which carry the tuning controls and tuning dial, to be adjusted with respect to the chassis. As mentioned above, this central unit, which carries 15 the tuning condenser, tuning control shaft and its associated control knobs, tuning dial, etc., should be floatingly mounted to avoid microphonics and undesirable vibration of the electrical parts which are sensitive to mechanical dis- 20 turbances. The commercial manufacture of such a floating mounting, however, requires broad tolerances in the mounting and makes it impossible to align exactly the tuning control shaft with the holes in the cabinet through which this tun- 25 ing shaft extends. By my invention, however, I have provided a means by which the position of the tuning shaft is made adjustable and thus the inaccuracies incurred by the required broad tolerances are overcome. It will be understood 30 that it is not necessary to have the entire unit adjustable, but my invention contemplates a tuning unit having a control shaft in which the front of the unit is pivotally mounted, and the rear of the unit is adjustably mounted so that 35 the position of the tuning shaft may be adjusted to compensate for the variations which will occur in the resilient mounting.

It is also characteristic of the R. F. unit B provided by this invention that the coils and wave- 40 band switches are mounted at the bottom of the unit within the box-like support 23 and are, therefore, placed further from and below the sources of heat in unit A. Moreover, the walls provided by the supporting bases of the several 45 units serve thermally to isolate the R. F. unit, particularly the coils and padding condensers thereof. It will be obvious that these walls, being heat conductive and heat reflecting, tend to carry the heat off or to radiate it so that the 50 heat is prevented from getting to the sensitive parts, such as the coils, padding condensers, etc. Moreover, the chimney-like structures above mentioned provide drafts of cool air flowing upward through the spaces 26, thus providing ventilation and cooling the walls of the R. F. unit, 55 as well as aiding in the dissipation of heat from the rectifier and A. F. output tubes.

The shaft 49 of the wave-band switches is re- 60 movably held in place by means of screws and indexing mechanism 51 (see Fig. 2).

The tuning condenser assembly 10 is mounted directly over the coil-switch assembly and is provided with terminal plates 30, so that the leads from the coil-switch assembly may be brought up 65 through openings in support 23 to the terminal plates. The tuning condenser assembly is mounted on front lugs 31 and rear support 32. To prevent straining the condenser frame, with 70 consequent variations in its electrical character- 75 istics, due to slight misalignment between the two front supports 31 and the rear support 32, such as might obtain in practice, the rear of the condenser assembly is resiliently mounted. This specific mounting of the tuning condenser assem- bly forms the subject of the copending applica-

As shown in Fig. 3, the supporting member 48 is secured to the rear bar 21, and also to the 40 flanges 16 and 19. Member 48 carries the resilient member 25. A screw 46 extends through member 25 and through a slot 53 in the rear wall of support 23 and threadedly engages an adjusting member 54. A sleeve 55 and metal 45 washer 56 prevents the screw from compressing the member 25, while the flange 57 on sleeve 55 also serves with member 54 to lock the parts in position. A lock washer 58 is preferably em- 50 ployed between member 54 and the wall of sup- port 23. It will be seen that the screw 46 may be variously positioned in slot 53 to effect the desired adjustment. It will be noted also that the unit B may be removed by simply removing screw 46.

In assembling the units, the R. F. unit B is readily mountable between the units A and C by virtue of the mounting provided. The flanges 16 and 19 are flared outward at their front portions, as shown at 41 in Figs. 1 and 4, and these flared 60 portions are provided with elongated openings 42 within which the resilient members 24 may seat. Each of these resilient members comprises a ring or washer of rubber or like material having a seating portion 43 and a flange 44, as shown in 65 Fig. 4. Each said member is secured to the side wall of the box-like support 23 by means of a flared stud 45 (see Fig. 5). The seating portion is adapted to seat in the elongated opening with which it is associated. It will be seen that in 70 mounting the unit B, the members 24 may be placed between the flared portions of flanges 16 and 19 and then drawn back into the openings in the closer portions of the flanges.

The washers 24 and 25 have their critical 75

dimension, i. e. the dimensions transversely of the axes of the washers, arranged so that they may be accurately defined by the mold in which the washers are formed, while the axial dimensions which are not critical are determined by the amount of material placed in the mold. This insures that the said critical dimensions will be accurate.

It will be seen that the unit A is made or built with the A. F. power output tube sockets 4 at the rear, and with the transformer 1 and rectifier tube socket 2 at the center, with the tube socket 2 mounted on top of the transformer, the electrolytic filter condensers 3 being at the front. The A. F. output tubes are one of the principal sources of heat in the receiver, and by positioning these tubes at the rear, the heat is dissipated most effectively, it being remembered that the back of a radio cabinet is usually open or well ventilated, whereas the front is closed. The power supply transformer and rectifier tube are also sources of a substantial amount of heat and hence they are positioned adjacent the output tubes. Moreover, the rectifier tube, which, in operation, is the hotter of the two, is mounted on top of the transformer, and the heat from the tube is thus radiated or dissipated rapidly. The power supply unit comprising the transformer and the rectifier tube forms the subject of my copending application, Serial No. 129,935, filed March 9, 1937.

This particular rectifier and transformer construction is useful in itself in minimizing the temperature rise of this particular apparatus. In addition, in the general structure shown, the hot parts are located generally above the thermally sensitive elements of unit B. Thus, in addition to assisting in forming a cooling draft through the chimney-like spaces 26, the positioning of this unit further serves to minimize the direct transfer of heat energy to the thermally sensitive elements.

Although a specific form of radio chassis has been illustrated and described, the invention contemplates broadly the floating mounting of a unit, including a tuning element having a control shaft, and the provision of means for adjusting the rear of said unit to permit variation of the position of said shaft. The invention also contemplates broadly the provision of chimney-like structures on opposite sides of the said unit.

From the above description, it will be seen that the invention provides novel features of construction which facilitate and simplify commercial manufacture of radio receivers and which greatly improve the operation of the receiver.

I claim:

1. In a radio receiver, a unit comprising a plurality of elements including a tuning element having a control shaft mounted on a common support or base, means for pivotally mounting the front of said support, said means comprising a pair of opposed pivotal mountings on opposite sides of said support, each of said mountings comprising a stationary flared wall with an elongated opening therein and a resilient member carried by said support adapted to be drawn into said open-

ings so as to seat therein, and means for adjustably mounting the rear of said support to permit variation of the position of said shaft.

2. In a radio receiver, a pair of interconnected spaced units forming a supporting structure, another unit disposed between said first-mentioned units, and means for floatingly and adjustably mounting said other unit in spaced relation with respect to said first-mentioned units, said means comprising a pair of front mountings, and a rear adjustable mounting carried by the supporting structure.

3. In a radio receiver, a pair of spaced walls, a unit having opposed side walls mounted between said spaced walls in spaced relation thereto, whereby chimney-like spaces are formed by the said walls on opposite sides of said unit, means for resiliently attaching the side walls of said unit to said spaced side walls, and means for resiliently mounting the rear of said unit.

4. In a radio receiver, a pair of spaced walls, a unit having opposed side walls mounted between said spaced walls in spaced relation thereto, whereby chimney-like spaces are formed by the said walls on opposite sides of said unit, means for resiliently attaching the side walls of said unit to said spaced side walls, and means for resiliently and adjustably mounting the rear of said unit.

5. In a radio receiver, a pair of interconnected spaced units having inner vertical walls spaced from one another, and another unit having opposed side walls mounted between said vertical walls in spaced relation thereto, whereby chimney-like spaces are formed by the said walls on opposite sides of said other unit.

6. In a radio receiver, a pair of interconnected spaced units having inner vertical walls spaced from one another, another unit having opposed side walls mounted between said vertical walls in spaced relation thereto, whereby chimney-like spaces are formed by the said walls on opposite sides of said other unit, means for resiliently attaching said side walls to said vertical walls, and means for resiliently mounting the rear of said other unit.

7. In a radio receiver, a pair of interconnected spaced units having inner vertical walls spaced from one another, another unit having opposed side walls mounted between said vertical walls in spaced relation thereto, whereby chimney-like spaces are formed by the said walls on opposite sides of said other unit, means for resiliently attaching said side walls to said vertical walls, and means for resiliently and adjustably mounting the rear of said other unit.

8. In a radio receiver, a pair of spaced walls having an open space therebetween, and a chassis unit having opposed side walls mounted between said spaced walls in spaced relation thereto, and providing unobstructed chimney-like passages between said first-mentioned walls and the walls of said unit on opposite sides of said unit, said passages creating drafts of cool air therethrough to cool and ventilate said unit.

DAVID GRIMES. 85
